INVENTOR

BY

Clarence Shook, *ATTORNEY*

UNITED STATES PATENT OFFICE.

EMANUEL W. HARTMAN, OF MIAMI, FLORIDA.

GAS-EXTRACTING APPARATUS.

Application filed July 20, 1921. Serial No. 486,313.

To all whom it may concern:

Be it known that I, EMANUEL W. HARTMAN, a citizen of the United States, and resident of Miami, in the county of Dade 5 and State of Florida, have invented a certain new and useful Improvement in Gas-Extracting Apparatus, of which the following is a specification.

This invention relates to an improvement 10 in gas extracting apparatus and particularly to that type in which the gas is extracted from shale, tar-sands and other bitumen containing material, the material being subjected to great heat and kept constantly in 15 motion.

One object of this invention is to provide 20 an apparatus which can be operated continuously to extract gas from bitumen containing material, and which is equipped with automatically operated feeding, advancing 25 and discharging mechanism.

Another object of this invention is to provide 25 means by which the material being treated is moved from one end of the heated retort to the other a plurality of times, thus insuring the extraction of all the gas possible therefrom.

Another object of this invention is to provide 30 a chain drag having plates which contact with and advance the material on both upper and lower runs.

A further object of this invention is the provision of a duplex apparatus having two 35 separately heated and operated charge handling compartments and a single intermediate compartment which acts as a cracking tower for the extracted gas from both compartments.

A still further object of this invention is 40 the provision of feed and discharge openings automatically controlled in order to reduce the entry of air into the retort to a minimum.

Other objects will appear from an examination 45 of the following description together with the drawings which are referred to therein and in which

Fig. 1 is a longitudinal sectional view taken on the line 1—1 of Figs. 2 and 7;

Fig. 2 is a cross sectional view taken on the line 2—2 of Fig. 1;

Figs. 3, 4 and 5 are detail views of the

chain drag, Fig. 4 being taken on the line 4—4 of Fig. 3;

Fig. 6 is a transverse sectional view taken 55 on the line 6—6 of Figs. 1 and 2;

Fig. 7 is a transverse sectional view taken on the line 7—7 of Figs. 1 and 2;

Fig. 8 is an elevation of one end of the apparatus partly in section on the line 8—8 60 of Fig. 2;

Fig. 9 is an elevation of the other end of the apparatus, and;

Figs. 10 and 11 are detail views of the 65 feeding mechanism.

The treatment of shale and other bitumen containing material in order to extract gas therefrom is carried out by means of a retort into which the material to be treated is subjected to great heat until the operation 70 is completed. The extracted gases are led off to a cracking tower, the exhausted charge is removed from the retort and a fresh charge supplied. This procedure is not new and has been followed for a number of years 75 particularly in Scotland. Originally the charge was not stirred during the heating operation but it has since been discovered that by the use of stirrers the output of gas is increased. When the retort is opened to 80 permit the removal of the exhausted shale and the introduction of a fresh charge air rushes into the retort and consequently the temperature drops so that the heat lost must be replaced before the full efficiency of the 85 retort is attained.

This present invention relates to certain 90 improvements in the above apparatus by which the retort is kept continuously in operation, the charge being fed and the exhausted material being removed at regular intervals with a minimum loss of heat. The charge is moved continuously while in the retort, from one end to the other a number 95 of times, by conveyors in the form of chain 95 drags, the plates thereof acting on the charge during both upper and lower runs.

Referring to the drawings reference numeral 20 is used to designate one form of furnace, preferably of brick that may be used to carry out this invention. Within the furnace 20 is the retort 21 which is made up of the compartments 22, 23 and 24. The shale to be treated is fed into the compart-

ments 22 and 24 and the gas extracted therefrom is led off through the compartment 23. A sheet metal lining 25 is provided for the retort in order to reduce the escape of heat through the brick walls 26 of the furnace.

Supported by standards 27 outside the furnace 20 and extending through the furnace are shafts 28, 29, 30, 31, 32 and 33. Three of these shafts pass through the retort 21 near each end. Each shaft is provided with two sprocket wheels 34, one in each of the shale treating compartments 22 and 24 and the sprocket wheels 34 in each compartment operate a chain conveyor or drag 35 for a purpose to be explained hereinafter.

The sets of wheels 34 with their conveyor 35 are separated in each compartment by horizontal partitions or shelves 36. These shelves are fixed to the end wall of the compartment adjacent the shafts 28, 29 and 30 and terminate in advance of the wheels 34 on the shafts 31, 32 and 33. The compartments are further divided by horizontal partitions or shelves 37 which extend from above the shafts 31, 32 and 33 to a point in advance of the sprocket wheels on the shafts 28, 29 and 30.

Each of the conveyors 35, illustrated in the drawings, is made up of a plurality of links 38 which, as shown in Figs. 3, 4 and 5, are integral plates bent down at each side to provide flanges 39 and a flat connecting top surface 40. The surface 40 is cut away at each end and through the projecting portions of the flanges 39 are made holes 41 for the fastening pins 42. One end of the link 38 is made narrower than the other end and sleeves 43 and 44 are provided to join the holes 41 in the narrower end. When assembled the flanges at the wider end extend at each side of the narrower end of the adjacent link so that the fastening pin 42 passes through one flange 39, the sleeve 43 and the other flange 39. The sleeve 44 is arranged between the flanges 39 to check any tendency of the flanges to collapse.

Mounted on each conveyer 35 are a plurality of equally spaced pushers or plates 45 by which the shale is moved over the shelves 37 on the upper run and over the shelves 36 and the bottom of the retort on the lower run. These plates 45 (see Figs. 3, 4 and 5) are made up of angle irons rigidly fixed to the top surfaces 40 of certain links. Riveted to the flange 46 of the angle iron 47 are angle irons 48 projecting at each side of the link 38. The angle iron 47 rests upon and is secured to the top surface 40, bolts 49 being shown on the drawings as used for that purpose.

In the walls 50 of the compartment 23 are provided rows of holes 51 just below the shelves 36 and 37 and the top plate of the compartments 22 and 24 so that all the gas

extracted from the charges passes off into the compartment 23. The walls 50 are fixed in position by apertured channeled bars 52 (see Fig. 2) and are secured to the lining 25 of the retort. A series of outlets 53 lead from the compartment to the pipe line 54 by which the extracted gas is taken to the gas treating apparatus where it is broken up and the gasoline and oil are separated out. While four outlets 53 are here shown united in pairs and then into a single line it is obvious that the number of outlets can be varied as found desirable.

Since one feed mechanism only is provided for both compartments 22 and 24 the walls 50 of the compartment 23 terminate short of the feed mechanism and are joined by an angled plate 55 so that the charge will not enter the compartment 23 but will be diverted to the proper compartments. Suitable plates 56 at each end of the plate 55 completely shut off the feed mechanism from the compartment 23.

The charge of shale or other bitumen containing material is fed into the retort by means of the trap mechanism 60 which is mounted in the top of the furnace equally distant from the sides and adjacent the end bearing the shafts 31, 32 and 33. This mechanism 60 comprises a cylindrical chamber 61 closed at the sides. In the top wall of the chamber is provided an inlet 62 while in the bottom wall is provided an outlet 63 diametrically arranged with relation to the inlet 62. Centrally mounted in the chamber 61 is a shaft 64 carrying a series of equally spaced vertical vanes 65. The shaft 64 is provided at its upper end with a bevel gear 66 which meshes with a bevel gear 67 fixed on a horizontal shaft 68. The shaft 68 is mounted in bearings 69 on the top of the furnace and is driven by power applied to the wheel or sprocket 70 at its outer end. The charge to be fed is conveyed to the mechanism 60 by the chute 71 from an ore crusher (not shown).

In the bottom plate 25 of each compartment 22 and 24 below the shaft 33 is provided an outlet 72 from which chute 73 leads to the discharge mechanism 74. This mechanism corresponds to the feed mechanism 60 described above and will therefore not be discussed in detail.

The vanes 75 in the trap 76 which carry the exhausted material from the inlet in the top wall to the outlet in the lower wall and thus to the chute 77 are actuated by a shaft 79 which is driven from a horizontal shaft 80 through the gears 81, the shaft 80 being supported by the bearing arm 82 and driven by power applied to the wheel or sprocket 83.

In the furnace 20 below the retort 21 are provided two fire boxes 84 and 85 by which the retort is heated. In order to insure suffi-

cient heat the fire boxes are located one at each end of the furnace below all three of the compartments. A brick wall 86 between the fire doors 87 separates the fire boxes. 5 In the side walls of the furnace 20 parallel to and substantially coextensive with the compartments 22 and 24 are provided flues 88 and 89 through which the hot air from the fire boxes 84 and 85 passes to the smoke stacks 90 and 91. The smoke stacks 90 and 91 are located at the middle of the flues and each flue is fed from both fire boxes through passages 92 at each end. Obviously therefore the heat from the boxes rises through 10 the passages 92 and passes along the outer walls of the compartments 22 and 24 so that they are kept at a high temperature. As pointed out above the fire boxes are under the compartment 23, referred to as a cracking tower, so that in case any of the heavier particles carried off by the gas drop they are reheated or "cracked" and pass off with 15 the rest of the gas.

The apparatus may be set in operation by 20 means of power applied to the wheel 93 on the shaft 30 by which the conveyor 35 and consequently the sprocket wheel 34 and shaft 33 are driven. A second wheel 94 on the shaft 30 by means of a belt or chain 95 actuates a wheel 96 on the shaft 29, and that shaft through the conveyor 35 actuates the shaft 32. The shaft 29 carries also a wheel 97 which through the belt or chain 98 sets in rotation the wheel 99 on the shaft 28. 25 The rotation is transmitted by the sprockets 34 and the conveyor 35 to the shaft 31. The shaft 31 carries adjacent one end a wheel 100 which is connected by a chain 101 with the wheel 70 on the shaft 68 by which 30 the feed mechanism is operated. On the shaft 31 adjacent the wheel 100 is a wheel 102 which through a chain 103 operates the wheel 83 on the shaft 80 which actuates the discharge mechanism.

40 The apparatus above described will be operated in the following manner. After the retort 21 has been heated by the fire boxes 84 and 85 to the desired temperature, between 1000° and 1500° the various parts are set in motion by application of power to the wheel 93. The material to be treated is fed by the chute 71 to the inlet 62 of the feed mechanism 60. As the vanes 65 swing around the material is shifted from below the inlet 45 62 to the outlet 63 thru which it drops onto the angled plate 55 and thence onto the upper shelves 37 in the compartments 22 and 24. The further movement of the material and the gas extracted therefrom is indicated by arrows on Figs. 1 and 7 and is, of course, the same in each compartment. The material on the shelf 37 is pushed along by the pushers 45 until it reaches the end of the shelf near the shaft 28. It then drops 50 to the shelf 36 where it is again pushed

along by the pushers 45 until the end of the shelf 36 near the shaft 31 is reached. The material again falls to the next lower shelf and the above operation is repeated until the now exhausted material passes down the 70 chute 73 to the discharge mechanism 74 and out of the furnace.

75 During its travel the material has been subjected to great heat so that all the volatile or semi-volatile elements have been driven off a gas through the openings 51, outlets 53 and pipe line 54, and has been stirred and agitated to such an extent that when it reaches the chute all the desired elements have been removed. 80

85 While one embodiment only has been shown and described applicant is not to be limited thereby since it is obvious that others can be made without departing from the spirit and scope of the invention as set forth in the following claims.

90 Having set forth my invention that which I claim as new and for which I desire the protection of Letters Patent of the United States is the following:

95 1. In an apparatus for extracting gas from bitumen containing material, a retort consisting of two compartments in which the material is treated, means for heating said retort, a third compartment between the first two situated directly over said heating means into which the gas extracted from the material in both said first named compartments escapes, said third compartment having a solid bottom and an outlet at the top 100 for said gas.

105 2. In an apparatus for extracting gas from bitumen containing material, a retort consisting of two compartments in which the material is treated, means for heating said retort, a third compartment between the first two, situated directly over said heating means into which the gas extracted from the material in both said first named compartments escapes, said third compartment 110 having a solid bottom and a single feeding means supplying both said first named compartments.

115 3. In an apparatus for extracting gas from bitumen containing material, a retort, means for heating said retort, a cracking tower comprising a compartment directly over said heating means within said retort having holes in its walls through which the gas extracted from the material contained in said retort enters the cracking tower and pipes for leading off the gas from said tower.

120 4. In an apparatus for extracting gas from bitumen containing material, a retort, means for heating said retort, a cracking tower comprising a compartment directly over said heating means within said retort adjacent a compartment in which the material is treated, openings through the wall 125 130

between said tower and said compartment, and pipes for leading off the gas from said tower.

5. In an apparatus for extracting gas from bitumen containing material, a retort consisting of two compartments in which the material is treated, means for heating said retort, a cracking tower comprising a

compartment directly over said heating means between said compartments, openings ¹⁰ in the walls between said tower and said compartments and pipes for leading off the gas from said tower.

In testimony whereof, I affix my signature.

EMANUEL W. HARTMAN.
